UNITED STATES PATENT OFFICE.

ERNEST SCHATTNER, OF SCHENECTADY, NEW YORK, ASSIGNOR TO GENERAL ELECTRIC COMPANY, A CORPORATION OF NEW YORK.

PREPAYMENT TIME-SWITCH APPARATUS.

No. 849,024.

Specification of Letters Patent.

Patented April 2, 1907.

Application filed June 23, 1905. Serial No. 266,549.

To all whom it may concern:

Be it known that I, ERNEST SCHATTNER, a subject of the King of England, residing at Schenectady, county of Schenectady, State 5 of New York, have invented certain new and useful Improvements in Prepayment Time-Switch Apparatus, of which the following is a specification.

The present invention relates to switch 10 apparatus for electric circuits, and more particularly to apparatus designed to complete a circuit or permit it to be completed for a definite period of time upon the prepayment of a proper coin. In many places where electric 15 energy is consumed in small quantities—as, for example, where the consumer burns two or three incandescent lamps—it is not desirable to provide an expensive wattmeter for recording the consumption. Under these 20 conditions it has been proposed to employ time-switch mechanism arranged to close a circuit upon the prepayment of a particular coin and to maintain it closed for a definite period thereafter.

The object of the present invention is to so 25 construct and arrange the parts of a switch apparatus adapted upon the insertion of a proper coin to supply current for a predetermined aggregate period of time which may 30 consist of any number of increments, that the apparatus shall be cheap, reliable in operation, and require no especial attention.

The present invention will be fully understood and further objects thereof will appear 35 in the following description thereof.

In the accompanying drawings, Figure 1 is a plan view of switch apparatus arranged in accordance with the present invention, the inclosing cover being removed. Fig. 2 is a 40 side elevation of the same. Fig. 3 is a longitudinal cross-section of the coin-controlled switch-operating device. Fig. 4 is a detail view of the main switch and the lever of the clock-stopping device, and Fig. 5 is a diagram 45 showing the location of the switch apparatus in a lighting-circuit including three lamps.

Similar reference characters throughout the specification and drawings indicate corresponding parts.

Reference being had to the drawings, 1 indicates a slab of insulating material, on one side of which is mounted a clockwork 2 of

any suitable construction, while on the other side are arranged switches 3 and 4 and co-operating parts. Switch 3 is the main switch controlled by the clockwork, and 4 is an auxiliary switch which may be opened or closed at will by the consumer. The switch 3 consists of a jaw 5 and a knife-blade 6. An arm 7, projecting from the member 6, forms therewith a bell-crank lever, which is pivotally mounted upon a shaft 8. When otherwise free, the switch member 6 moves with the shaft 8 by reason of a spring connection between this member and the shaft, which comprises a spring 9, secured at its opposite ends, respectively, to the switch-blade 6 and to an arm 10, rigidly secured to the shaft and projecting therefrom, the switch-blade normally resting against one side of said arm. The switch members 5 and 6 are so arranged that after the blade has been forced home the shaft 8 may be turned in a counter-clockwise direction without opening the switch, thereby placing the spring 9 under tension. The shaft is operated in the switch-closing direction by means of a button 11, which extends to the exterior of the inclosing casing. (Not shown.) The button 80 is connected to the shaft through the two clutch members 12 and 13, which engage with each other, but are not connected together. The members 12 and 13 are provided, respectively, with narrow slots 14 and 15, which 85 when the two members are placed in operative relation to each other form a passage of the proper dimensions for receiving the coin with which prepayment is to be made. Normally the button 11 may be turned without 90 affecting the shaft 8; but when it is turned so as to bring the slot 15 into alignment with slot 14 a coin may be dropped through a chute 16 into the slots 14 and 15, locking the button to the shaft. A shield 17, arranged 95 on the lower side of the parts 12 and 13, sustains the coin until the lower portion of the slots pass the edge 19 of the shields, whereupon the coin is released and drops into the bottom of the casing. The length of the 100 shield is such that the movement of the shaft before the coin is released is sufficient to wind up the spring 18 of the clockwork and bring the switch-blade 6 into engagement with the jaw 5, as shown in Figs. 1 and 4. 105 The movement of the button 11 is limited by

a shoulder 13^a on the member 13, this shoulder coöperating with suitably-spaced fixed stops, which may be the edges of the shield 17. Normally the clockwork is locked 5 against operation by means of a wire-stop 20, which engages with the teeth of the balance-wheel 21 of the clockwork. The stop 20 is carried upon one end of a pivoted lever 22, which when the switch 3 is open occupies the position shown in dotted lines in Figs. 1 and 4, being held in this position by the arm 7. When the switch 3 is closed, however, the lever 22 is rotated to the position shown in full lines in Figs. 1 and 4 by 10 means of the spring 23—namely, to the position wherein the stop 20 is out of engagement with the balance-wheel. It will be seen, therefore, that as soon as the proper coin is inserted and the button 11 turned until the 15 coin drops into the bottom of the box the clockwork is set in operation, turning the shaft backward, and at the end of a predetermined time bringing it to its normal position. As previously stated, the switch 3 will 20 remain closed, due to the frictional engagement between its parts, so that the retrograde movement of the shaft does not of itself open the switch. When the shaft 8 has been returned through the entire angle 25 through which it was previously moved by the button 11, a lug 24 strikes against the switch-blade 6 and positively disengages it from the jaw 5. The spring 9, being under considerable tension, withdraws the blade 30 suddenly, producing an instantaneous break. At the same time the arm 7 flies into engagement with the lever 22 and depresses it into the position shown in dotted lines—namely, into the position wherein the clockwork is 35 locked against operation.

If no additional means were provided, the entire amount of energy credited to the consumer upon deposit of the proper coin would have to be consumed in one continuous interval. It may, however, be desired to use only a small portion of this energy at any one time, and for this purpose switch 4 has been provided. This switch comprises, preferably, a snap-switch of any usual or desired 45 form arranged to be operated by means of a button 25, which also is adapted to project from the inclosing casing for the apparatus. The function of the switch 4 is to interrupt the circuit when desired and at the same 50 time to stop the clock in order that the main switch may remain closed until current has been supplied for the whole period of time. To this end the movable member 26 of the switch 4 is arranged to operate upon the lever 22 to move it to the locking position whenever the switch 4 is open. This may of course be accomplished in various ways—as, for example, as illustrated, whereby a curved 55 pivoted rocker 27 is arranged with its respective ends in the path of movement of the

member 26 and lever 22. When the switch 4 is closed, the rocker 27 is readily swung about its pivot by the lever 22 and does not interfere therewith; but upon the opening of the switch 4 one end of the rocker is engaged by the movable member of the switch, causing the rocker to be swung upon its pivot and its opposite end to engage with and move the lever 22 to locking position.

Although I have illustrated the present invention as arranged to operate on single coins only, it is obvious that with slight modifications any number of coins may be inserted, providing for a corresponding increase in the amount of energy which will be supplied before the switch 3 is opened.

It will also be understood that various modifications may be made in the construction and arrangement of the parts illustrated without departing from the scope of the present invention, and I do not desire to be limited to the particular construction and arrangement of parts shown except to the extent indicated in the appended claims.

What I claim as new, and desire to secure by Letters Patent of the United States, is—

1. In a prepayment time-switch apparatus, two switches electrically connected in series and operable entirely independently, a clockwork for opening one of said switches, means for closing this switch and winding the clockwork, and means for automatically stopping said clockwork when either of said switches is opened.

2. In a prepayment time-switch apparatus, two switches electrically connected in series and operable entirely independently, a clockwork for opening one of said switches, manually-operable means for closing this switch and winding the clockwork, and means for automatically stopping said clockwork when either of said switches is opened.

3. In a prepayment time-switch apparatus, two switches electrically connected in series and operable entirely independently, a clockwork for opening one of said switches, a winding-shaft having a limited movement for closing this switch and winding the clockwork, and means for automatically stopping said clockwork when either of said switches is opened.

4. In a prepayment time-switch apparatus, a switch, a clockwork for opening said switch, a winding-shaft having a limited movement, means associated with said shaft for causing said switch to close when said shaft is moved to one limit of its movement and to cause the switch to open when the shaft is brought to its other limit of movement, and means for operating said shaft to close the switch.

5. In a prepayment time-switch apparatus, a switch, a clockwork for opening said switch, a winding-shaft having a limited movement, means associated with said shaft for closing

and opening said switch at the opposite limits of movement of the shaft, and means for operating the shaft to close the switch.

6. In a prepayment time-switch apparatus, a switch, a clockwork for opening said switch, a winding-shaft having a limited movement, and means associated with said shaft whereby the movable member of the switch is placed under tension during the movement of the shaft from the switch-closed to the switch-open position.

7. In a prepayment time-switch apparatus, a switch, a clockwork for opening said switch, a winding-shaft having a limited movement, means associated with said shaft for causing said switch to close when said shaft is moved to one limit of its movement and to cause the switch to open when the shaft is brought to its other limit of movement, means for rotating the shaft to close the switch, and means for stopping the clockwork when the switch is in the open position.

8. In a prepayment time-switch apparatus, a switch, a clockwork for opening said switch, a winding-shaft having a limited movement, means associated with said shaft for causing said switch to close when said shaft is moved to one limit of its movement

and to cause the switch to open when the shaft is brought to the other limit of its movement, means for operating the shaft to close the switch, a second-switch, and means associated with said second switch for stopping said clockwork when the second switch is opened.

35

9. In a prepayment time-switch apparatus, a switch, a clockwork for opening said switch, a winding-shaft having a limited movement, a switch member mounted upon said shaft, a complementary switch member mounted to rotate with said shaft and arranged to engage with the movable switch member when the shaft is rotated in one direction, and a spring connecting said movable switch member and said complementary switch member whereby when the shaft is rotated by the clockwork the spring is placed under tension and an instantaneous break at the switch is produced.

In witness whereof I have hereunto set my hand this 22d day of June, 1905.

ERNEST SCHATTNER.
